1

The present invention relates to rotary selector switches for use in automatic telephone exchanges and the like, and more particularly to selector switches for use in systems wherein line finding is accomplished by capacitive testing, without the use of galvanic contact between elements of the selector incoming line and elements of the various outgoing lines of the selector.

Selectors are known in which, when the selector is free, the brushes connected to the incoming line are at rest with respect to the stationary contacts of the selector outgoing lines. These brushes are mounted on a rotor and are set in motion when the selector operates to find a line. The brushes are then stopped against the contacts of the desired outgoing line in order to connect such desired outgoing line to the incoming line of the selector.

In some known selector systems (cf. French Patent 822,910 and Swiss Patent 219,816), some of the rotor brushes are arranged so that, during their rotation, they have no frictional contact with the rows of outgoing line stator contacts associated therewith. Similarly, as to such brushes, there is no frictional contact during motion between the rotor incoming line electrodes connected to these brushes and the fixed contacts connected to the wires of the selector incoming line, galvanic contact being established only when the selection is made.

Even in these known systems however it is still necessary that at least one rotor brush have frictional contact with the stator contacts of its row, and that at least the rotor incoming line contact connected to that brush have frictional contact with its associated fixed incoming line contact.

For, if the desired outgoing line is identified by a particular electric state of the contact pins of one or more rows of stator outgoing line contacts, this electric state must be transmitted to the device which governs motion of the selector by means of precisely such contact.

If instead according to another known form of construction the selector operates step by step so that the desired outgoing line is identified by the number of steps executed by the brushes in starting from a zero position, it is still necessary that at least one rotor brush possess galvanic contact with the outgoing line stator contacts of the stator row associated with that brush and that the incoming line rotor electrode connected to that brush possess galvanic contact with the incoming line stator contact associated there-

2

with in order to ensure a systematic return of the rotor to its zero position when the selector is released.

These frictional contacts, even when thus restricted to a small number of the elements of the selector, consume energy and are a cause of wear. If the contact pressures are reduced to minimize these mechanical disadvantages, the resultant electrical contact is unsatisfactory.

10 The present invention provides a rotary selector with semicircular rows of outgoing line stator contacts arrayed one above another into a semi-cylindrical surface and in which the rotor scanning brushes which explore the panel of stator outgoing line contacts so formed are incorporated into a rotor which moves at uniform velocity with respect to the stator when the selector is free. The rotation is stopped when the selector makes selection of a desired outgoing line. During rotation the rotor scanning brushes travel past the outgoing line stator contacts without mechanical contact therewith. These scanning brushes are connected within the rotor to incoming line rotor electrodes, preferably of approximately circular shape, which are capacitively associated and not mechanically connected during such rotation with stator electrodes connected to the wires of the selector incoming line. In the course of a selection, 15 characteristic voltages applied to selected stator contacts of each outgoing line are capacitively induced upon the rotor scanning brushes which move past them, and these potentials are then capacitively passed from the rotor incoming line 20 electrodes connected to these brushes and to the stator incoming line contacts. Upon the identification of the desired outgoing line by comparison of the voltages so obtained upon wires of the selector incoming line with chosen reference voltages, through the intervention of suitable identification means such for example as that described in my copending application Serial No. 208,794, filed January 31, 1951, rotation of the rotor is stopped, and certain other 25 rotor contacts are brought into galvanic contact with appropriate outgoing line contact pins in the stator. At the same time the rotor incoming line electrodes are brought by axial translation of the rotor into firm galvanic contact with stator incoming line contacts so as to effect galvanic contact between the respective wires of the selector incoming line and those of the chosen outgoing line. With the construction of the invention, to be described in 30 further detail below, the contact pressures ob-

35

40

45

50

55

tained after selection are much higher than those available in rotary selectors of the prior art. Moreover, according to the invention certain contacts auxiliary to the talking circuit to be established are made or broken without the help of relays or other auxiliary devices. For example advantage is taken of the axial motion of the selector rotor upon the making of a selection to provide directly a holding circuit for the stopping coil by means of which the rotor is stopped and held in fixed position once the desired outgoing line has been found.

Because of the indeterminate values of the wiring capacities involved, the voltages transmitted from a selector according to the invention to the input terminals of an identification means as described above will not in general be a constant fraction of the characteristic identification voltages applied to the selector outgoing line stator contacts. Within the identification means therefore the line-characteristic identification voltages can therefore be identified dependably only by their polarity, in the case of D. C. voltages, or by their frequency in the case of A. C. voltages. Since D. C. voltages thus possess only three characteristic values: positive, zero and negative, they would permit selection of only a restricted number of lines or line groups.

If more than two or three lines or line groups are to be identified, it is therefore necessary to employ A. C. identification voltages. This will usually be the case for selectors employed as either group selectors or final selectors. In an exchange therefore, for which the selectors of the invention are designed, each outgoing line or line group is identified by a particular frequency or frequencies of the identification voltages which are applied to one or more of the stator contacts of that line as it appears as an outgoing line of a selector according to the invention. To set up a desired circuit the selector rotor is stopped to effect galvanic connection between the wires of the selector incoming line and the wires of a free outgoing line the characteristic frequency or frequencies of which have been determined to be identical to a predetermined reference frequency or frequencies, chosen by a recorder or sender storing the signals generated by a calling subscriber's dial, for example. In my copending application Serial No. 208,794, filed January 31, 1951, I have described frequency identification means having two input terminals to which are applied A. C. voltages of varying frequency and having an output across which there is developed a D. C. voltage signal when and only when the input voltages are of the same frequency.

In order for such identification means to be able dependably to identify the frequencies of the voltages scanned from the outgoing line stator electrodes, it is necessary that the period of the lowest identification frequency employed be short compared to the time required for the passage of the rotor scanning brush past one of the stator electrodes held to such an identification voltage. For this reason and further to prevent disturbance of the actual communication channels by such identification voltages, the latter are all selected above the audio range, and preferably above 10 kilocycles.

The use of such high frequencies for the identification voltages requires that precautions be taken to minimize their mixing by capacitive induction among the wires of the various outgoing lines which carry these voltages to the stator contacts of the selectors of the invention. In

particular, the multiplying together of a plurality of selectors by means of flat fan-shaped groups of wires radiating in each selector from the contacts of a single semicircular row cannot be employed since it does not permit the use of proper electrostatic shielding to prevent such induction. For, even with electrostatic shields between the adjacent fan-shaped bundles, the wires of each bundle constitute wires of a single function drawn from a large number of outgoing lines, and certain bundles would precisely combine together the wires of a plurality of outgoing lines held to the different identification voltage frequencies of those lines. According to the invention therefore multiplying wires are grouped not according to function but according to azimuth, bringing together all the wires of one outgoing line or of the small number of outgoing lines whose contacts occupy a single azimuthal position or vertical row in the selector stator. The bundles are therefore made up parallel to the selector axis rather than perpendicular thereto.

The invention will now be further described in detail with reference to the accompanying drawings in which:

Fig. 1 is a view in side elevation of the outgoing line stator elements of a single azimuth of a plurality of selectors according to the invention, multiplied together;

Fig. 19 is a schematic view of the rotor elements of a selector according to the invention with the stator elements for a single azimuth, shown in connection with certain other elements of a switching system with which the selector of the invention is adapted to cooperate, and

Fig. 20 is a partial sectional view in plan of a selector according to the invention showing the outgoing line stator contacts and electrodes of two horizontal rows in the stator bank and the rotor brushes and contacts which cooperate therewith.

As is illustrated in Figs. 1 and 11 the selectors of the invention are adapted to be combined into columns of selectors which are multiplied together according to well-known principles. Figs. 1 and 11 show elements of four selectors only. A large number of selectors may of course be provided in the column.

The stator of each selector includes flange or frame members 2 and 3 as illustrated in Figs. 2 and 4 supporting a plurality of outgoing line stator contact assemblies 10 of the type illustrated in Figs. 7 and 8. Each selector further includes stationary elements associated with the selector incoming line and a rotor adapted to effect contact between the wires of the selector incoming line and the wires of any one of the outgoing lines which is brought to the selector via one of the assemblies 10. The rotor, rotor drive and rotor stopping mechanism (Fig. 16), and the stationary incoming line elements (Fig. 17) are removably associative with the frame members 2 and 3 in which the bank of stator outgoing line contacts are fastened. The assemblies 10 are disposed in a semicircular array, each assembly defining an azimuth for the selector stator. In the embodiment illustrated each assembly 10 includes contacts and identification frequency electrodes for two outgoing lines.

Referring now to Fig. 6, each assembly 10 is composed of a parallel array of multiplying wires 4, an insulating plate 5 and a plurality of transverse bars some of which terminate in galvanic contact pins 8 and the remainder of which terminate in scanning electrodes 7 perpendicular to the length of the wires 4, the aggregate number of the bars being equal to the number of multiplying wires 4. In the example illustrated there are provided eight pin-shaped terminals 8 and six electrodes 7, having the form and function of condenser plates. The insulating plates 5 are perforated so as to give one access to each of the multiplying wires 4 and each of the bars makes electrical contact with one of the wires 4 through such a perforation. The junctions are suitably soldered or welded to ensure good electrical contact. The bars are preferably made of a material such as Phosphor bronze having good mechanical as well as electrically conducting properties. Away from their ends 7 and 8 they may be scored as shown to improve their adhesion in the enveloping plastic. The combination of the wires 4, plate 5 and transverse bars is then suitably laminated or embedded in an insulating material such as polymethacrylate to

form an assembly 10 of rectangular section as shown in Figs. 7 and 8. Customarily for economy of construction the wires 4 are made of a length suitable to the number of selectors to be built into the column desired so that a series 1 of assemblies 10 are formed integrally together, the number of assemblies 10 in the series being equal to the number of selectors to be provided in the column.

10 Referring to Figs. 2 to 5, the flanges 2 and 3, which may for example be die cast of an aluminum alloy, are provided with a plurality of radial slots 12 between fingers 14, the number of slots being equal to the number of assemblies 10

15 to be provided in the selector. In the embodiment shown, fifty slots are arranged over a semicircular arc, each slot accommodating an assembly 10 which gives access to two outgoing lines.

A column of selectors is assembled by fastening a double plurality of the flanges 2 and 3 in suitable order to frame members such as angle irons 18 (Fig. 13). The series 1 of assemblies 10 as fragmentarily illustrated in Fig. 1 are then inserted into the slots 12. The plastic coating 20 in which the assemblies 10 are embedded may be provided with grooves 11 adapted to fit over the upper and lower flanges of each selector to provide suitable mechanical rigidity.

To prevent crosstalk electrostatic shielding is 30 provided between adjacent assemblies 10 by means of thin metallic foils 48 (Fig. 13) applied to one face of each of the entire series of assemblies 10 before insertion into the flanges. Precautions are then taken to ensure good electrical 35 contact between the foils 48 and the fingers 14 in the flanges to provide multiple ground points for the foils. Wedges 13 may be inserted with the assemblies 10 in the slots 12. These are particularly helpful where the assemblies are 40 made of rectangular section, as in the embodiment shown in Figs. 7 and 8.

The aspect of the resulting column of selector outgoing line elements is illustrated in Figs. 11 through 13 in which for simplicity only a small number of the contacts, foils and multiplying wires 45 have been shown.

Figs. 14 and 15 illustrate a complete selector according to the invention. This includes not only the bank of outgoing line stator elements 50 hitherto described but also the incoming line stator elements, the rotor by means of which selection and contact between the incoming line and a chosen outgoing line is made, and the rotor driving and stopping means. The multiplying wires 4 have been omitted from Fig. 15.

In addition to the outgoing line stator elements, formed into banks as shown in Fig. 11, the selector of the invention comprises an incoming line stator contact assembly 30, a rotor 20, a driving mechanism 21 and a rotor stopping mechanism 19, all illustrated in Fig. 16. The stopping mechanism 19 comprises a plate 22, a cup 23, and a male cone 24 all concentric with each other and forming together a magnetic circuit adapted to be energized by a rotor stopping coil winding 35. The cup 23 is secured to the plate 22 by means of screws 25 and the cone 24 is secured thereto by means of screws 26. The plate and cup may be split as at 36 in Fig. 17 to reduce eddy currents. Over one half of its circumference the plate 22 has the same radius as the cup 23 but over the remainder of its circumference its radius is slightly greater, providing a supporting flange 27 terminating at abutments 28 located on 60 opposite ends of a diameter of the plate 22. The

flange 27 is employed to support the stopping mechanism 19, incoming line contact assembly 30, rotor 20 and driving mechanism 21 from the frame 3, where it fits into a semicircular groove 72 in which it is held by a semicircular ring 73 (Figs. 4 and 14). The elements 22, 23 and 24 are made of soft iron. The stopping mechanism 19 supports the incoming line stator contact assembly 30 comprising a block 430 of insulating material on which are supported the incoming line stator contacts of the selector (Figs. 16 and 17). These contacts (shown schematically in Fig. 19) take the form of a plurality of semicircular rings 31, 131, 231 and 331 concentric with each other and with the axis 403 of the selector. The rings 31, 131, 231 and 331 are axially separated and further include or have respectively connected thereto, radially extending contact blades 32, 132, 232 and 332 for the making of galvanic contact with the rotor incoming line contacts as will be subsequently described. In addition, auxiliary contact blades 233 and 333 on block 430 form intermittent contacts with the blades 232 and 332. Thus 232 and 233 form a pair of normally closed contacts, i. e. closed during rotation of the selector. The elements 332 and 333 form a pair of normally open contacts which are closed only upon the axial translation of the selector rotor which occurs when selection is made. The semicircular rings 31, 131, 231 and 331 and the blades 233 and 333 are provided with extensions 34 (Fig. 17) to permit the attachment of conductors in any usual and suitable manner.

Referring now to Figs. 14, 15, 16 and 19 the selector rotor 20 comprises a molded plastic member 83 of rotationally symmetric shape. A stem-like cylindrical portion 39 fits with clearance at bore 439 over the selector drive shaft 63 and supports a soft iron female cone 40 which completes the magnetic circuit with the cup 23 and the male cone 24. The stem 39 further supports rotor incoming line contacts in the form of circular rings 41, 141, 241 and 341 for capacitive and galvanic association with the incoming line stator rings and contact blades previously described. A conical surface 42 is formed on the end of the stem 39 opposite the cone 40. The stem is extended into a mushroom-like plate 43. At opposite ends of a diameter of the plate 43 there are formed axially extending supports 45 and 45' whose cross section is illustrated in Fig. 18. The support 45 provides support to the rotor scanning brushes 50, 150, 250 and contacts 51, 151, 251 intended for association with one of the outgoing lines brought to each vertical row of stator contacts. The support 45' carries the rotor brushes and contacts adapted for association with the other outgoing line of each outgoing stator azimuth. Thus the support 45 has embedded therein or otherwise affixed thereto scanning brushes 50, 150 and 250 and contact members 51, 151, 251 and 351. The contacts 51, 151, 251 and 351 are each provided with a lip 80 (Fig. 18) adapted to bring up against the round pins 8 of the bank of outgoing line stator pins and the scanning brushes 50, 150 and 250 form variable condensers with the outgoing line stator electrodes 7 in moving past them. This is schematically illustrated in Fig. 19, in which the outgoing line stator elements having reference characters whose last digit is 8 are in position to be engaged by lipped or curled rotor brushes and in which the scanning brushes 50, etc., are adjacent to plate-shaped members the

last digit of whose reference characters is 7. The second support 45' similarly carries scanning brushes 50', 150' and 250' and galvanic contact electrodes 51', 151', 251' and 351'. Connection is provided between the rotor incoming line electrodes 41, 141, 241 and 341 on the one hand and the pairs of brushes and contacts 50, 51; 50', 51', etc., by means of wires 60 embedded in the supports 45 and 45' and passing through the cylindrical plate 43.

The driving mechanism for the rotor of the selector of the invention is illustrated in Fig. 16. A shaft 63 of steel or the like carries two sets of ball bearings 64 and 65. The bearing 64 journals the shaft in the cone 24 and hence via the plate 22 the shaft is supported in the selector frame. Similarly the bearing 65 supports the shaft in the lower stator flange 2, as indicated in Fig. 15. A cone 66 is drawn up tight against a shoulder 463 on the shaft by means of a ring 67. The cone 66 therefore turns with the shaft. The ends of the shaft 63 are rectangular or hexagonal as indicated at 71 and engage with clutch plates 68. Coil springs 69 are provided to expand the clutch plates outwardly from the selector for engagement with the corresponding clutch plates of the adjacent selectors in a column.

When the removable assembly shown in Fig. 16 is fastened together with its bank of stator outgoing line contacts to form a complete selector, the flange 27 of the plate 22 (Fig. 17) slips into a semicircular groove 72 in the upper flange 3 (Figs. 4 and 14). A retaining ring 73 is then applied about the edge of the plate and is fastened to the flange by means of the screws 74 (Fig. 14). At the other end of the rotor shaft 63 the outer race of the bearing 65 fits into a semicircular bearing 76 formed in the lower flange 2 where it is retained by means of the bearing cap 77, fastened to the flange by means of screws 78 (Figs. 2 and 15).

Fig. 14 illustrates the engagement between adjacent selectors in a column by means of the clutch plates 68. The plates 68 may have roughened surfaces 70 to ensure the transmission of rotation from the one shaft 63 to the next and so on throughout the entire column. At one end of the column a prime mover such as an electric motor transmits uniform rotation to the first selector in the column.

With the selector so assembled, the rotor 20 of any one selector can turn with its shaft 63, or it may be held fast with respect to its stator. The shaft 63 turns at all times at constant speed under the control of a motor, not shown, which may be of conventional type. When a plurality of selectors according to the invention are assembled into a column, the motor is located at one end of the column and is connected by clutch means to the shaft of the selector nearest it. Referring to Fig. 16, while the selector is free, and during the process of line finding, the coil 35 is de-energized and the rotor 20 rests of its own weight on the cone 66 by which it is centered to carry its scanning brushes 50, 50', 150, 150', etc., uniformly past the plate-shaped identification voltage electrodes of the outgoing line stator bank. When selection is made, the coil 35 is energized, and rotor 20 is lifted by the action of the resultant magnetic field on the cone 40 of magnetic material. The cones 40 and 24 again assure proper centering of the rotor. A slightly greater clearance between the cones 24 and 40 than that between the pin-shaped out-

going line stator contacts such as 38, 38', etc., (Fig. 19) and the rotor contact brushes 51, 51', etc., produces flexure of the latter when the rotor is lifted, resulting in excellent electrical contact.

The selector is schematically shown in Fig. 19 with certain associated elements, particularly the identification means and the recording means or sender.

Fig. 19 illustrates the outgoing line contacts for one azimuth or vertical row in the stator bank and shows two output lines each including seven contacts of which three are of flat plate form to cooperate with the scanning brushes of the rotor and of which four may be conventional round pins for galvanic contact upon the stopping of the rotor. The contacts of flat plate form are Nos. 31, 137 and 237 for the first outgoing line and 37', 137' and 237' for the second outgoing line. The pin contacts are Nos. 38, 138, 238 and 338 for the first outgoing line and 38', 138', 238' and 338' for the second outgoing line.

The wires of the first outgoing line comprise wire O, the busy condition test wire connected to contacts 237 and 338; wire T, the duplicate selection test wire connected to contact 238; and wires A and B, the talking conductors of the line which are connected respectively to contacts 38 and 138. The wire D, which is connected to the contact 137 is held by the source 85 at an alternating identification voltage of a frequency f_d characteristic of the tens digit of the first line of the azimuth shown, and the wire U, which is connected to contact 37, is held by the source 86 at an alternating voltage of frequency f_u characteristic of the units digit of the first line of the azimuth shown.

The corresponding wires of the second outgoing line are designated by the same capital letter reference characters with primes to distinguish them from the wires of the first outgoing line. They connect respectively with stator outgoing line contacts of the same numbered reference characters, again primed. Thus the source 85' generates and applies to the contact 137' an alternating voltage of a frequency f_d' characteristic of the tens digit of the second outgoing line of the azimuth shown, and the source 86' generates and applies to the contact 37' an alternating voltage of frequency f_u' characteristic of the units digit of the second outgoing line for the azimuth shown.

The incoming line includes four wires. Wire o is the busy wire, grounded through the battery 104. Wire t is the duplicate selection test wire and a and b are the talking conductors. The wire o is connected to the stator incoming line half-ring 331 and to its connected contact blade 332. Wire t is connected to half-ring 231 and to contact blade 232, wire b to half-ring 131 and to contact 132, and wire a lastly is connected to half-ring 31 and to contact blade 32.

The rotor comprises ring 41 connected to two diametrically opposite pairs of brushes 50, 51 and 50', 51'. It also includes the ring 141 connected to two diametrically opposite pairs of brushes 150, 151 and 150', 151'; the ring 241 connected to two diametrically opposite pairs of brushes 250, 251 and 250', 251'; and the ring 341 connected to two diametrically opposite brushes 351 and 351'.

As indicated in Fig. 19, where the rotor is shown in the axial position which it occupies during continuous rotation, which position may func-

tionally be called the "rest position," the rotor brushes sweep past the fixed contacts of the stator without galvanic contact with them. In Fig. 19, the stator contacts designated with primed reference characters are axially displaced with respect to those with unprimed reference characters and similarly the primed and unprimed rotor members are axially displaced with respect to each other. With this construction each revolution of the rotor permits scanning of a number of output lines equal to twice the number of azimuth intervals provided on the stator.

In the description of operation of the selector of the invention now to be given it will be assumed that the desired output line is the first output line shown in Fig. 19, its conductors being designated A, B, T, O, and D and U. The alternating voltage sources 85, 85' and 86, 86' of the azimuth shown, as well as those of other azimuths, are connected to a recording means 103 or sender as well as to the plate-shaped test electrodes of their respective lines in the selector stator contact bank. The sender may be of the type described in my copending application Serial No. 208,794 and the details of which form no necessary element of the present invention. For the description of the present invention it will suffice to state that in consequence of the dialing by calling subscriber the sender 103 chooses among the plurality of frequencies applied to it the frequencies f_d and f_u . It then applies the frequency f_d to the wire 101, and the frequency f_u to the wire 102.

An identification means 87, which may be of the type described in my copending application above referred to, includes two input terminals 88 and 92 and an output terminal 96. The input 88 is connected to the armature blade 89 of the relay 100 whose associated fixed contacts 90 and 91 are respectively connected to the talking conductors a and b of the selector incoming line. The input terminal 92 is connected to the armature contact 93 of relay 100 whose corresponding fixed contacts 94 and 95 are respectively connected to the conductors 101 and 102. The output terminal 96 is connected to the armature contact 97 of relay 100 whose corresponding fixed contacts 98 and 99 are respectively connected to the coil of relay 100 and to the wire t of the incoming line.

During rotation of the selector the brush 150, which is positioned two azimuth intervals ahead of the other rotor brushes as shown in Fig. 20, scans the voltages of the various plate-shaped contacts of the row represented by the contact 137. The potentials so scanned are applied via the wire b and contacts 91 and 89 to the input terminal 88 of the identification means. When the potential experienced by the brush 150 is of the same frequency as that applied to the input terminal 92 of the identification means from the sender 103 via wire 101 and contacts 94 and 93 of relay 100, a D. C. voltage appears at the output terminal 96. This voltage, applied through contacts 97 and 98 energizes relay 100 and connects the input terminal 88 to the wire a and input 92 to wire 102.

As the selector continues to rotate the brush 50, disposed one azimuth interval in advance of the other rotor brushes, scans the voltages of the various outgoing line stator contacts in the row occupied by the contact 31. The potentials so scanned are applied via wire a and contacts 89 and 90 of relay 100 to the input terminal 88 of the identification means 87. When the voltage experienced by the brush 50 is of the same fre-

quency as that applied to the input terminal 92 from the sender 103 via wire 102 and contacts 95 and 93, a D. C. voltage appears at the output terminal 96. This D. C. voltage is applied via contacts 97 and 99 of relay 100 to the wire *t* of the selector incoming line.

By virtue of the contact existing between stator contacts 232 and 233 this voltage is applied across the coil 35 and effects axial translation of the rotor in the sense of the arrow 81. Thus the selector rotor is lifted off the cone 66 into engagement with the cone 24 (Fig. 16). In the course of this translation contact is made between 332 and 333 to provide a holding circuit by the coil 35 via the incoming line wire *o*, battery 104, and economizer resistance 105. The cones 24 and 40 engage and center the rotor in a "busy" position in which it is at rest. In the busy position, the lipped brushes 51, 151, 251 and 351 are respectively applied to the pin-shaped contacts 38, 138, 238 and 338 of the desired out-going line. The lips 80 (Fig. 18) of the brushes 51, 151, 251, and 351 prevent rotation of the rotor past the desired azimuth. The incoming line *a*, *b*, *t*, *o* is consequently galvanically extended to the outgoing line A, B, T, O via the contact established between 51 and 38, 151 and 138, 251 and 238 and 351 and 338.

A pointer 82 (Figs. 14 and 15) affixed to the cap 77 indicates the azimuthal position of the rotor while at rest by reference for example to a scale applied to the exterior cylindrical surface 43 of the rotor.

What I claim is:

1. A selector comprising a frame, a bank of outgoing line stator contacts arranged in vertical and horizontal rows in a substantially semicylindrical inwardly facing array fixed in the frame, all stator contacts of each outgoing line being located in one vertical row and each of a plurality of outgoing lines connected to the selector having in one horizontal row of the bank a condenser plate-shaped contact, each of said lines having in each of two other horizontal rows a pin-shaped contact, two arcuate incoming line stator contacts supported coaxially with said array, two stator contact blades connected one to each of said incoming line stator contacts, an annular electromagnet supported coaxially with the array, a rotor driving shaft journaled in the frame coaxially with said array, rotor supporting means on said shaft, a rotor including an armature adapted to cooperate with said magnet, said rotor being freely engaged on said shaft, said rotor being shaped to rest on said rotor supporting means with clearance from said magnet, two ring-shaped incoming line rotor contacts mounted coaxially with the rotor in position to rotate adjacent the arcuate incoming line stator contacts when said rotor rests on said supporting means, a scanning brush connected to one of said incoming line rotor contacts and supported on the rotor in position to move past the condenser plate-shaped contacts of the bank when said rotor rests on said rotor supporting means, and an outgoing line rotor contact brush connected to each of said incoming line rotor contacts, said outgoing line rotor contact brushes being in a single azimuth of the rotor displaced from the azimuth of said scanning brush by the interval separating two or more vertical rows in the bank, each of said outgoing line rotor contact brushes being adapted upon energization of said magnet to engage galvanically a pin-shaped contact of one of said other horizontal rows in

the bank, and each of said incoming line rotor contacts being adapted upon energization of said magnet to engage galvanically one of said contact blades.

5. A selector comprising an outgoing line stator contact bank conforming to a substantially semicylindrical surface in which all electrodes belonging to any one outgoing line are arranged along a line parallel to the axis of the said surface, the electrodes of said bank belonging to one outgoing line including in addition to contacts for the talking conductors of the line at least one electrode of flat plate shape disposed substantially perpendicular to the axis of the said surface and adapted to form one of the plates of a condenser, a plurality of selector incoming line contacts of semicircular ring shape supported coaxially of the said surface, a rotor mounted coaxially of the said surface for rotation relative to said bank and for translation between first and second positions axially of said bank, a plurality of ring-shaped electrodes affixed to the rotor in position to move in planes adjacent the planes of the selector incoming line contacts but without contact therewith upon rotation of the rotor when in its first axial position, a scanning brush of flat plate shape adapted to form one of the plates of a condenser, said brush being supported on the rotor in position to sweep past the flat plate electrodes of the bank but without contact with said flat plate electrodes upon rotation of the rotor when in its first axial position, said scanning brush being connected to one of the ring-shaped rotor electrodes, a plurality of galvanic contact brushes supported on the rotor in position to effect galvanic contact with contacts of the bank upon axial translation of the rotor from its first to its second axial position, said contact brushes being each connected to one of said ring-shaped electrodes, driving means engaging the rotor in its first axial position to rotate the same, and means to translate the rotor axially from its first to its second axial position.

3. A selector comprising a bank of outgoing line stator contacts disposed over a portion of a circularly cylindrical surface in vertical rows parallel and in horizontal rows perpendicular to the axis of said surface, the contacts of each outgoing line being arranged in a single vertical row, a horizontal row of plate-shaped electrodes in said bank, the contacts of a plurality of other horizontal rows being respectively connected to the talking conductors of a plurality of outgoing lines, a plurality of incoming line stator contacts at least two of which are of arcuate shape disposed coaxially of said surface, a rotor mounted coaxially of said surface for rotation relative to said bank and for translation from a first to a second axial position relative to said bank, a plurality of incoming line rotor contacts of circular ring shape supported on the rotor coaxially of said surface, a rotor scanning brush connected to one of said incoming line rotor contacts, a plurality of outgoing line rotor contact brushes connected each to one of said incoming line rotor contacts, driving means to rotate the rotor when in its first axial position, and translation means adapted to move the rotor axially and to disengage it from said driving means, the rotor and the contacts and brushes supported therein being so dimensioned that when said translation means is not actuated the rotor turns without galvanic contact with any stator contact, said rotor scanning brush being moved past the horizontal row of plate-shaped contacts in

the stator bank and said incoming line rotor contacts rotating respectively adjacent said arcuate incoming line stator contacts.

4. A selector for automatic telephone exchanges comprising a bank of outgoing line stator contacts arranged in vertical and horizontal rows in a substantially semicylindrical inwardly facing array, each vertical row including all the outgoing line stator contacts for two outgoing lines and including two contacts of plate shape, one for each of said lines, and further including four pin-shaped contacts, two for each of said lines, two incoming line stator electrodes of semicircular ring shape supported coaxially with said array, two contact blades connected one to each of said incoming line stator electrodes, a rotor mounted for rotation coaxially with the array and for translation with respect thereto between first and second axial positions, two incoming line rotor electrodes of circular ring shape mounted in the rotor coaxially therewith and positioned to rotate adjacent the incoming line stator electrodes when the rotor is in its first axial position, two diametrically opposite rotor scanning brushes connected to each other and to one of the incoming line rotor electrodes and axially displaced from each other in position to rotate with the rotor each past one of the horizontal rows of plate-shaped contacts in the array when the rotor is in its first axial position, a first pair of outgoing line rotor contact brushes axially spaced apart by the separation of at least two horizontal rows of pin-shaped contacts in the array and connected each to one of the incoming line rotor electrodes, a second pair of outgoing line rotor contact brushes diametrically opposite the first, the contact brushes of said second pair being axially separated by the spacing of the other two horizontal rows of pin-shaped contacts in the array and connected each to one of the incoming line rotor electrodes, driving means to rotate the rotor, and means to lift the rotor from its first to its second axial position and to disengage it from the driving means, whereby when said rotor lifting means is not actuated the rotor turns with the driving means without galvanic contact between any electrical stator element and any electrical rotor element, and whereby upon actuation of said rotor lifting means said incoming line rotor electrodes are stressed against said contact blades and said outgoing line rotor contact brushes are stressed against pin-shaped contacts of the array.

5. A selector comprising a plurality of outgoing line stator contact panels of plastic material each including a plurality of contacts connected to multiplying wires, said contacts including at least one salient electrode of flat plate shape and at least two salient contact pins, upper and lower slotted frame members adapted to support the panels in a substantially semicircular array with said contacts on the inner surface of the semicylinder, conducting metallic foils interposed between adjacent panels, an annular electromagnet fastened to the upper of said frame members, a drive shaft journaled in the magnet and in the lower of said frame members coaxially with said array, a cone affixed to said shaft below the magnet, a rotor loosely fitting about said shaft between said magnet and said cone, a collar of magnetic material affixed to said rotor adjacent said magnet, a plurality of incoming line stator electrodes of semicircular ring shape supported from said magnet coaxially with regard to said shaft, a plurality of ring-

shaped incoming line rotor electrodes, a rotor scanning brush connected to one of said incoming line rotor electrodes, and two rotor contact brushes, said rotor scanning and contact brushes being so dimensioned that when said magnet is not energized the incoming line rotor electrodes rotate respectively adjacent the incoming line stator electrodes with the scanning brush sweeping past the plate-shaped outgoing line stator electrodes, all without galvanic contact between elements of the rotor and stator, whereas upon energization of said magnet the rotor is lifted from the cone and stopped with the contact brushes in contact with outgoing line stator contact pins and with the incoming line rotor electrodes in contact with incoming line stator electrodes.

6. A selector comprising a frame, a bank of outgoing line stator contacts arranged in at least three horizontal rows and in a plurality of vertical rows in a substantially cylindrical inwardly facing array fixed in the frame, one of said horizontal rows including contacts of substantially flat plate shape adapted to act as condenser plates, two arcuate incoming line stator contacts supported coaxially of said array, an electromagnet supported from the frame, a rotor driving shaft journaled in the frame coaxially of the array, rotor supporting means arranged on the shaft, a rotor including an armature adapted to cooperate with the magnet, the rotor being freely engaged on said shaft and being shaped to rest on said supporting means with clearance between said armature and magnet, two ring-shaped incoming line rotor contacts mounted coaxially of the rotor, a scanning brush in the rotor connected to one of said incoming line rotor contacts, and two outgoing line rotor contacts in the rotor connected each to one of said rotor incoming line contacts, said brush, rotor outgoing line contacts and rotor incoming line contacts being so positioned in the rotor that when said rotor rests on said supporting means said brush rotates with clearance past the contacts of said one horizontal row to form condensers therewith successively, said rotor outgoing line contacts rotate past the contacts of said other two horizontal rows without galvanic contact therewith, and said rotor incoming line contacts rotate past said stator incoming line contacts to form condensers therewith continuously, and when said magnet is energized said rotor and stator incoming line contacts are brought into galvanic contact and said rotor outgoing line contacts are brought into galvanic contact with contacts of said other two horizontal rows.

7. A selector comprising a bank of outgoing line stator contacts arranged in a plurality of vertical and in a plurality of horizontal rows in a substantially cylindrical inwardly facing array, one of said horizontal rows including contacts of flat plate shape oriented parallel to right sections of the array, said contacts being adapted to form condenser plates, a plurality of arcuate incoming line stator contacts supported coaxially of said array, an electromagnet supported in fixed position relative to said array, a rotor driving shaft journaled coaxially of the array, rotor supporting means on said shaft, a rotor including an armature adapted to cooperate with said magnet, said rotor being freely engaged on said shaft and shaped to rest on said supporting means with clearance between said armature and magnet, a plurality of pairs of rotor contacts arranged in the rotor, each such pair including

a ring-shaped incoming line contact coaxial of the rotor connected to an outgoing line rotor contact, at least one of said pairs, including a rotor outgoing line contact of substantially flat plate shape oriented perpendicularly to the axis of the rotor, said rotor outgoing line contact of flat plate shape being adapted to form condensers with said flat plate shaped stator outgoing line contacts successively, said rotor contacts being so positioned in said rotor that when 10 said rotor rests on said supporting means said rotor rotates with said drive shaft without galvanic contact between any stator incoming line contact and any rotor contact and without galvanic contact between any rotor contact and any 15 stator outgoing line contact but with the plate-shaped contacts of the rotor moving past the plate-shaped contacts of the stator closely adjacent thereto, whereas upon energization of said

magnet at least two rotor incoming line contacts engage galvanically two stator incoming line contacts and the rotor outgoing line contacts connected to said two rotor incoming line contacts engage galvanically stator outgoing line contacts of different horizontal rows.

ETIENNE ALIZON.
